UNITED STATES PATENT OFFICE

DEWEY T. SIMONDS, OF SCHENECTADY, NEW YORK, ASSIGNOR TO GENERAL ELECTRIC COMPANY, A CORPORATION OF NEW YORK

ELECTRON-DISCHARGE DEVICE

Application filed July 20, 1925. Serial No. 44,654.

My present invention relates to electron discharge devices, and more particularly to devices of the four electrode type. The present application is directed to improvements over the devices of that type described and claimed in United States patent application, Serial No. 695,665, filed by Albert W. Hull, March 3, 1924, and assigned to the same assignee as the present application.

It is well known that in the usual three electron discharge device there is an appreciable capacity between the grid and anode, and that by reason of this capacity the amplifying effect of the device particularly at high frequencies may be greatly reduced. This capacity coupling also provides a feedback which tends to cause the production of self sustained oscillations in the circuits associated with the device.

In order to overcome this difficulty it has been proposed to employ a fourth electrode known as a screening grid which is interposed between the control grid and the anode. By impressing a positive potential upon this screening grid of a suitable value, the effects of capacity coupling between the control grid and the anode may be reduced. In order to entirely eliminate this capacity effect, however, precautions must be taken in the construction of the device to eliminate the effect of capacity coupling between the current supply conductors to the electrodes as well as the capacity between the electrodes themselves.

The object of my invention is to provide an efficient structure for an electron discharge device whereby the effects of the capacity coupling between the electrodes and the leads which supply current to the electrodes may be entirely eliminated.

The novel features which I believe to be characteristic of my invention are set forth with particularity in the appended claims. My invention itself, however, both as to its organization and method of operation will best be understood by reference to the following description taken in connection with the accompanying drawing in which Fig. 1 is a cross sectional view of a device which may be used in carrying my invention into effect;

Fig. 2 is a cross sectional view of a modification; Fig. 3 is a cross-sectional view taken along the line 3—3 of Fig. 1, and Fig. 4 is a cross-sectional view taken along the line 4—4 of Fig. 2.

I have indicated in Fig. 1 of the drawing an electron discharge device comprising a tubular evacuated receptacle 1 in which are enclosed an electron emitting cathode 2, an anode 3, a control grid 4, and a screening grid 5.

The screening grid 5, which is preferably of cylindrical form made up of fine wire wound round and secured to supporting rods has at its ends two metallic cylindrical members 6 and 7. Member 6 embraces a body of insulating material 8, which closes that end of the screening grid, and member 7 surrounds and embraces a reentrant tubular member 9, which forms a part of the receptacle 1. The screening grid is supported from the reentrant tubular member 7, being clamped thereto by a suitable clamp 10. Current supply members 11, 12, and 13 for the screening grid and cathode are sealed into reentrant tubular member 9. A second current supply conductor for the cathode passes through the insulating member 8 and is brought down to the base of the tube and sealed therein at 14. The anode 3 is supported independently of the other electrodes by means of springs 15 interposed between it and the wall of the receptacle 1. A current supply conductor 16 for the anode is sealed into the base of the receptacle at 17 and connected to the shell 18 of a 4-contact base. For convenience of illustration this base has been shown with the contacts all in line, but in practice it will be preferable to have the contacts arranged in the usual manner.

To avoid the effect of capacity coupling between the current supply conductor 12 for the control grid and the current supply conductor 16 for the anode, the metal shield 19 is provided. This shield extends into the reentrant tubular member 9 and overlaps the cylindrical member 7. It is provided with a depending portion 20 which surrounds the contacts 21. This depending portion 20 is

adapted to fit into a cylindrical member 22, which is secured to the socket 23 and which surrounds the contact members 24.

The cylindrical member 22 is also joined conductively to the metallic plate 25 on the bottom of the socket and the shielding effect obtained may be extended by mounting the socket 23 upon a metal panel 26. If the shielding structure is connected to ground then an effective shield is provided between the current supply conductors for the control grid and the current supply conductors for the anode. Circuit connections to the anode may be completed by means of a suitable connection, not indicated, to the socket shell 27.

In the form of my invention shown in Fig. 2, reentrant tubular members 28 and 29 are provided at both ends of the receptacle. The screening grid 5 is supported from these two members in a manner similar to that employed in the form of my invention shown in Fig. 1. The current supply conductor 30 for the anode is sealed into one end of the receptacle at 31 and the current supply conductor 32 for the screening grid is sealed into the same end of the receptacle at 33. Current supply conductor 34 for the control grid is sealed through the reentrant tubular member 28 and connected to a circuit connector 35, which may be secured to but insulated from a metal shell 36 adapted to enclose the entire device. Shielding members 37 and 38 embrace both ends of the receptacle 1 and extend into the reentrant tubular members 28 and 29 over-lapping the cylindrical members 6 and 7, which form the ends of the screening grid 5. The current supply conductor 39 for one end of the cathode 2 is connected to one of the base connections while the current supply conductor 40 to the other end of the cathode is conductively connected to the shielding member 37. When the shell 36 is in the position shown, contact is established by means of the spring fingers 41 between the members 36 and 37 and thus a circuit is formed between the current supply conductor 40 and shell 42 of the base which is connected to one of the base contact members. In the operation of the device the shell 42 and the screening members described will preferably be connected to ground and thus a grounded shielding system will be provided which will supplement the action of the screening grid and eliminate the effects of all capacity coupling between the anode and control grid. Since circuit connection for the control grid is established at the opposite end of the device from that of the anode capacity coupling between the external circuits of the two electrodes may readily be avoided.

While I have shown and described two different modifications of my invention whereby the desired results may be secured, it will, of course, be understood that many modifications in the structures employed may be made

without departing from the scope of my invention as set forth in the appended claims.

What I claim as new and desire to secure by Letters Patent of the United States is:—

1. The combination in an electron discharge device of an evacuated receptacle of insulating material which encloses an electron emitting cathode, an anode, a control grid and a screening grid interposed between the anode and control grid, said screening grid having the form of a cylinder having its ends completely closed by members of insulating material, current supply conductors for the cathode and control grid which are sealed into said members of insulating material, a four contact base connected to one end of said receptacle, connections between the contacts on said base and supply conductors for the cathode, anode and screening grid, and means at the opposite end of said receptacle for establishing a circuit connection to the supply conductor for the control grid.

2. The combination in an electron discharge device of an evacuated receptacle of insulating material which encloses an electron emitting cathode, an anode, a control grid and a screening grid interposed between the anode and control grid, said screening grid having the form of a cylinder having its ends completely closed by members of insulating material, current supply conductor for the cathode and control grid which are sealed into said members of insulating material, a four contact base connected to one end of said receptacle, connections between the contacts on said base and supply conductors for the cathode, anode and screening grid and means at the opposite end of said receptacle for establishing a circuit connection to the supply conductor for the control grid, said base comprising a metallic shell through which connection may be established between one of the cathode supply conductors and one of the base contacts.

3. The combination in an electron discharge device of an evacuated receptacle of insulating material which encloses an electron emitting cathode, an anode, a control grid and a screening grid, interposed between the anode and the control grid and a reentrant tubular member at each end of said receptacle, said screening grid having the form of a cylinder whose ends are supported by and completely closed by said reentrant tubular members and metallic members which embrace the ends of said receptacle and extend into said reentrant tubular members.

4. The combination in an electron discharge device of an evacuated receptacle of insulating material which encloses an electron emitting cathode, an anode, a control grid and a screening grid interposed between the anode and the control grid and a reentrant tubular member at each end of said receptacle, said screening grid having the form

of a cylinder whose ends are supported by and completely closed by said reentrant tubular members metallic members which embrace the ends of said receptacle and extend into said reentrant tubular members and a shielding member which encloses said receptacle and which is conductively connected to said metallic members.

5. The combination of an electron discharge device comprising an evacuated receptacle of insulating material which encloses an electron emitting cathode, an anode, a control grid and a screening grid interposed between the anode and control grid and conductive means within the receptacle connected to the screening grid and mounted to act in conjunction with the screening grid to eliminate capacity coupling between the anode and control grid, and a conductive shielding member which surrounds said device and supplements the effect of the screening system within the receptacle in eliminating undesirable capacity coupling.

6. The combination of an electron discharge device comprising an evacuated receptacle of insulating material which encloses an electron emitting cathode, an anode, a control grid and a screening grid interposed between the anode and control grid and conductive means within the receptacle connected to the screening grid and mounted to act in conjunction with the screening grid to eliminate capacity coupling between the anode and control grid, a conductive shielding member which surrounds said device and supplements the effect of the screening system within the receptacle in eliminating undesirable capacity coupling, a current supply conductor for the control grid which extends through one end of said conductive shielding member and current supply conductors for the other electrodes which extend through the opposite end of said conductive shielding member.

45. 7. The combination of an electron discharge device comprising an evacuated receptacle of insulating material which encloses an electron emitting cathode, an anode, a control grid and a screening grid interposed between the anode and control grid and conductive means within the receptacle connected to the screening grid and mounted to act in conjunction with the screening grid to eliminate capacity coupling between the anode and control grid, a conductive shielding member which surrounds said device and supplements the effect of the screening system within the receptacle in eliminating undesirable capacity coupling, and a contact on said conductive shielding member which contacts with a contact on the receptacle to complete a circuit connection to one of the electrodes.

8. The combination of an electron discharge device comprising an evacuated re-

ceptacle of insulating material which encloses an electron emitting cathode, an anode, a control grid and a screening grid interposed between the anode and control grid and conductive means within the receptacle connected to the screening grid and mounted to act in conjunction with the screening grid to eliminate capacity coupling between the anode and control grid, a conductive shielding member which surrounds said device and supplements the effect of the screening system within the receptacle in eliminating undesirable capacity coupling, and a contact on said conductive shielding member which contacts with a contact on the receptacle to complete a circuit connection to the control grid.

In witness whereof, I have hereunto set my hand this 17 day of July, 1925.
